AUTOMATIC OILER FOR AIR PUMPS

James O. Ivie, Salt Lake City, Utah
(7165 Delaware St., Riverside, Calif.)

Filed July 3, 1958, Ser. No. 746,538

5 Claims. (Cl. 230—207)

The present invention relates to a unit that is attached to an air pump to provide means for automatically supplying oil to the intake air to the pump and for removing oil from the exhaust air from the pump.

Herefore, several devices have been suggested for adding oil to the inlet air of an air pump. The continuous flow of oil from the pump in the exhaust air therefrom is a constant source of trouble, as it softens the rubber connection, or clogs the metal pipe, if metal pipes are used. Means for removing this oil and recirculating it through the pump have not heretofore been incorporated in a single unit.

It is an object of this invention to supply a single unit to admit oil to the inlet air to an air pump and remove the oil from the exhaust air from said pump.

It is also an object of this invention to provide an oil reservoir having transparent sides so that the flow of oil and the condition of the oil may be subject to visual inspection.

It is a further object of this invention to provide within the reservoir an air port in the high pressure line that causes the air to flow against the sides of said reservoir in a line that is tangential thereto.

A still further object of this invention is to provide a filtering means between the high pressure inlet and the high pressure outlet to remove the oil from the air stream.

The various features of novelty which characterize this invention are pointed out with particularity in the claims annexed hereto and forming a part of this specification. For a better understanding of the invention, however, its advantages, and specific objects obtained by its use, reference should be had to the accompanying drawings and descriptive matter in which is illustrated and described a preferred embodiment of the invention.

In the drawings:

Fig. 1 is a side elevation of the oiler unit.

Fig. 2 is a top plan view of Fig. 1.

Fig. 3 is an enlarged vertical section on line 3—3 of Fig. 2.

Fig. 4 is a horizontal sectional view on line 4—4 of Fig. 3.

Fig. 5 is a fragmentary sectional view on line 5—5 of Fig. 3.

Fig. 6 is a fragmentary sectional view similar to Fig. 5 of a modification for regulating the fluid flow.

Fig. 7 is a sectional view similar to Fig. 3 of a further modification.

Fig. 8 is a schematic view showing the operation of the device.

The first embodiment of the invention illustrated in the drawings comprises the main body of the unit 10, shown in Fig. 1. Attached to this is the high pressure air inlet 11 and the high pressure air outlet 12. Also attached to this main body 10 is a low pressure air inlet 14. Attached to the under side of this body 10 is a reservoir 15 held in air-tight connection with the body 10 by means

2

of the neoprene gasket 16 retained on the under side of said body. Said reservoir is held in position against the body by means of the metal straps 17, 17, shown in Figs. 1 and 4, which are held on the body by the bolts

18, 18. There is an expansion unit at the bottom of these straps comprising a threaded stud 19, shown in Fig. 3, with the threaded nut 20 thereon, which may be brought to bear against the bottom of the reservoir 15 through the elastomeric cushion 21.

10 The high pressure inlet air is admitted through the air inlet 11 and passes through the body down into the reservoir 15 through the nozzle 22. This nozzle has a side opening 23 and a restricted bottom opening 23', which will admit the air with entrained oil therein in a line that is against and at an angle to the inside surface of the reservoir 15, and causes the flow of air therethrough to circulate in a cyclonic manner around the interior surface of the reservoir 15, thereby depositing the entrained oil on the interior surface of the reservoir. The air is exhausted from this reservoir through the outlet 12.

20 The low pressure air to the air pump is admitted to the body 10 through the low pressure inlet 14 and passes through the body to the pump, through the low pressure outlet 13. Between the inlet 14 and the outlet 13 this low pressure air picks up a quantity of oil which is preferably admitted by means of the wick 24, shown in Figs. 3 and 4, which passes through the conduit 25 to the body 10 and comes in contact with the low pressure air within this passage through the body.

30 The reservoir 15 is preferably made of a transparent material, such as glass or a transparent plastic such as methacrylate, but may be made of a non-transparent material, such as metal.

35 The flow of oil up the wick into contact with the low pressure is caused by the differences in pressure between the inside of the reservoir 15 and the low pressure conduit 25 in the top of the body. This means of feeding the oil is shown in Figs. 3 and 5, but a second modification is also within the scope of this invention, as

40 shown in Fig. 6, wherein the low pressure air inlet 26 leads to a low pressure conduit 27 and to the low pressure outlet 28, through the body 10. The conduit 27 has an opening in the bottom thereof which leads, by means of a conduit 29 to the oil in the reservoir 15.

45 Across the top of this conduit 29 is a needle valve 30 threaded into the body 10 and held in position by means of lock nut 31 and adjustable by means of the knurled head 32.

A third modification is shown in Fig. 7, wherein a porous filter 33 surrounds the conduit 25 and is held in position against the neoprene washer 34, by means of the spring 35. The neoprene washer 34 surrounds the high pressure outlet so that the entering air in addition to being forced against the side of the reservoir 15 must also pass through the centered porous filter made of fused glass, frit or Carborundum in the usual manner. The degree of porosity of this filter may be selected so as to give the proper filtering action and at the same time not create too high a resistance to the air flow there-

60 through.

In operation, a pump 36, having the air intake conduit 37 is connected to the main body 10, as shown in Fig. 8. The exhaust, or high pressure side of the pump has a conduit 38 connected to the main body as shown. The air entering the conduit 37 passes through the main body, picks up the oil from the wick 24, passes through the pump and lubricates the same, is exhausted through the high pressure conduit 38 into the oil through the opening 23 into the glass reservoir 15. It circulates around the inside of the reservoir and is exhausted through the high pressure conduit 39. The pressure within the reservoir

forces the oil through the wick 24 within the conduit 25 so that the oil may be picked up by the intake air at the top of the oiler.

While in accordance with the provisions of the statutes there has been illustrated and described the best forms of embodiment of this invention, it will be apparent to those skilled in the art that changes may be made in the forms of the apparatus disclosed without departing from the spirit of this invention as set forth in the appended claims and that in some cases certain features of this invention may be used without corresponding uses of other features.

What is claimed is:

1. A combination of an air pump and a unitary lubricating oiler, said air pump having a low pressure air inlet and a high pressure air outlet, said lubricating oiler comprising a body portion and an oil reservoir held in air-tight relationship with said body portion, said body portion having a low pressure conduit therethrough operatively connected to the low pressure air inlet of said pump and the atmosphere, said low pressure conduit having a branch conduit leading to the bottom of said reservoir and having means therein to restrict the flow of oil to said low pressure conduit from said reservoir, said body portion having a high pressure conduit centrally located therein operatively connecting the interior of said reservoir to the said high pressure air outlet of said pump, said high pressure conduit having a nozzle within said reservoir near the top thereof to discharge the incoming air tangentially to the interior side surface

of said reservoir, said body portion having a second high pressure conduit therein leading from the upper part of said reservoir to an air outlet delivery port.

2. A device as claimed in claim 1, wherein there is a porous filter within said oil reservoir, said reservoir being transparent separating the high pressure air inlet from the high pressure air outlet.

3. A device as claimed in claim 1, wherein the flow of oil from the reservoir to the low pressure conduit is regulated by means of a valve.

4. A device as claimed in claim 1, wherein the flow of oil from said reservoir to said inlet air is regulated by means of a wick.

5. A device as claimed in claim 1, wherein the means for admitting a constant supply of oil to said air inlet is surrounded within the reservoir by a porous filter comprising a fused granular material.
